Attest.

United States Patent Office.

SYLVESTER J. TUCKER, OF PHILADELPHIA, PENNSYLVANIA, ASSIGNOR TO J. ADAM RUSH, OF SAME PLACE, FOR ONE-HALF HIS RIGHT.

Letters Patent No. 91,690, dated June 22, 1869.

IMPROVEMENT IN WRITING-DESK CALENDAR.

The Schedule referred to in these Letters Patent and making part of the same.

To all whom it may concern:

Be it known that I, SYLVESTER J. TUCKER, of the city and county of Philadelphia, and State of Pennsylvania, have invented a new and useful Combined Writing-Desk (or Inkstand-Case) and Calendar; and I do hereby declare that the following is a full, clear, and exact description thereof, sufficient to enable others skilled in the art to which my invention appertains, to make and use the same, reference being had to the accompanying drawings, in which—

Figure 1 is a front elevation of the combined writing-desk, or inkstand-case, and calendar.

Figure 2, a rear view of the dial-plate, showing the calendar-mechanism.

This invention consists in so combining the calendar-mechanism with the locking-catch of a writing-desk, that by the turning of the key which releases the catch, the wheels composing the calendar-mechanism are rotated, and indicate, by pointers, on suitable dials, the day of the week, the day of the month, the name of the month, and the year, as will be hereinafter fully described.

In the drawings—

A represents the case of the writing-desk and calendar.

B represents the door of the case, which may be hinged at its lower edge, and is provided with a suitable knob, a.

Above the knob a, on the inside of the door, is placed the catch-plate, which receives a catch, b, on the "square" c.

On this "square" is also fixed an eccentric arm, d.

As the "square" c is turned, by means of a suitable key, to release the catch, the arm d raises a pivoted lever, e, to the opposite ends of which are jointed pawls or detents, f g.

The pawl f, engaging with the teeth of a ratchet-wheel, n, pushes the latter the distance of one tooth each time the lever e is raised.

The ratchet-wheel n has thirty-one teeth, corresponding to the number of days in a month, and on the outer end of its arbor is fixed a pointer, which moves around over a dial divided into thirty-one spaces, properly numbered.

At each operation of the lever e, the detent g, engaging with the teeth of a ratchet-wheel, i, rotates said wheel the distance of a tooth.

The wheel i is made with seven teeth, one for each day of the week, and an index on its arbor points to the designated space on the dial.

j is a wheel having twelve teeth, one for each month of the year. This wheel receives motion by the following means:

A tappet, k, on wheel n, once in each revolution of said wheel, in other words, once a month, comes in contact with the teeth of a wheel, l, having twelve teeth, and turns the same one-twelfth of a revolution.

This wheel l gears with the wheel j, also having, as above stated, twelve teeth, corresponding to the number of months in a year, and each partial rotation of wheel l imparts the same (one-twelfth revolution) to wheel j, which carries on the outer end of its arbor an indicator, which points out the name of the month.

A tappet, o, on wheel l, comes, once during the revolution of said wheel, or, once a year, in contact with a wheel, h, and turns the same the space of one tooth.

The teeth on this wheel may be of any desired number, according to the range of years throughout which it is intended that the calendar shall be correct.

A pointer on the arbor of wheel h indicates the current year.

The arbors of the day, week, month, and year-wheels may project at the rear, so that they can be adjusted, should occasion require.

It is necessary that the arbor of the day-wheel thus project, because, when the month is composed of less than thirty-one days, the pointer t must be adjusted separately.

When the period of years marked on the dial p has expired, a new dial can be substituted, and the usefulness of the calendar thus extended indefinitely.

q represents a spring, which keeps the lever e in the position shown, and thus controls the catch.

A spring, r, shown in red in fig. 1, causes the door to fly open as soon as unlocked.

If desired, a pen-rack may be fixed inside the door.

The advantages of my invention will be appreciated when it is remembered that the adjustment of detached calendars is frequently overlooked, and trouble thereby occasioned.

Having thus described my invention,

What I claim as new, and desire to secure by Letters Patent, is—

In combination with the fastening-device of a writing-desk, the calendar-mechanism herein described, consisting of the pivoted lever e and pawls f g, operated by means of an arm on the "square" c, whereby the unlocking of the desk will move the pointers of the calendar, in the manner and for the purpose set forth.

To the above I have signed my name, this 8th day of March, 1869.

SYLVESTER J. TUCKER.
